(57) **CLAIM**

The ornamental design for a sock as shown and described.

DESCRIPTION

FIG. 1 is a perspective view of a first embodiment of a sock with the text of New York, showing our new design;

FIG. 2 is a front elevational view corresponding to FIG. 1; FIG. 3 is a rear elevational view corresponding to FIG. 1; FIG. 4 is a left side elevational view corresponding to FIG. 1; FIG. 5 is a right side elevational view corresponding to FIG. 1; FIG. 6 is a top elevational view corresponding to FIG. 1; FIG. 7 is a bottom elevational view corresponding to FIG. 1; FIG. 8 is a perspective view of a second embodiment of a sock with the text of Denver, showing our new design; FIG. 9 is a front elevational view corresponding to FIG. 8; FIG. 10 is a rear elevational view corresponding to FIG. 8; FIG. 11 is a left side elevational view corresponding to FIG. 8; FIG. 12 is a right side elevational view corresponding to FIG. 8; FIG. 13 is a top elevational view corresponding to FIG. 8; FIG. 14 is a bottom elevational view corresponding to FIG. 8; FIG. 15 is a perspective view of a third embodiment of a sock with the text of Los Angeles, showing our new design; FIG. 16 is a front elevational view corresponding to FIG. 15; FIG. 17 is a rear elevational view corresponding to FIG. 15; FIG. 18 is a left side elevational view corresponding to FIG. 15; FIG. 19 is a right side elevational view corresponding to FIG. 15; FIG. 20 is a top elevational view corresponding to FIG. 15; FIG. 21 is a bottom elevational view corresponding to FIG. 15; FIG. 22 is a perspective view of a fourth embodiment of a sock with the text of Arizona, showing our new design; FIG. 23 is a front elevational view corresponding to FIG. 22; FIG. 24 is a rear elevational view corresponding to FIG. 22; FIG. 25 is a left side elevational view corresponding to FIG. 22; FIG. 26 is a right side elevational view corresponding to FIG. 22; FIG. 27 is a top elevational view corresponding to FIG. 22; FIG. 28 is a bottom elevational view corresponding to FIG. 22; FIG. 29 is a perspective view of a fifth embodiment of a sock with the text of Chicago, showing our new design; FIG. 30 is a front elevational view corresponding to FIG. 29; FIG. 31 is a rear elevational view corresponding to FIG. 29; FIG. 32 is a left side elevational view corresponding to FIG. 29; FIG. 33 is a right side elevational view corresponding to FIG. 29; FIG. 34 is a top elevational view corresponding to FIG. 29; FIG. 35 is a bottom elevational view corresponding to FIG. 29; FIG. 36 is a perspective view of a sixth embodiment of a sock with the text of California, showing our new design; FIG. 37 is a front elevational view corresponding to FIG. 36; FIG. 38 is a rear elevational view corresponding to FIG. 36; FIG. 39 is a left side elevational view corresponding to FIG. 36; FIG. 40 is a right side elevational view corresponding to FIG. 36; FIG. 41 is a top elevational view corresponding to FIG. 36; FIG. 42 is a bottom elevational view corresponding to FIG. 36; FIG. 43 is a perspective view of a seventh embodiment of a sock with the text of Colorado, showing our new design;

FIG. 44 is a front elevational view corresponding to FIG. 43; FIG. 45 is a rear elevational view corresponding to FIG. 43; FIG. 46 is a left side elevational view corresponding to FIG. 43; FIG. 47 is a right side elevational view corresponding to FIG. 43; FIG. 48 is a top elevational view corresponding to FIG. 43; FIG. 49 is a bottom elevational view corresponding to FIG. 43; FIG. 50 is a perspective view of a eighth embodiment of a sock with the text of Miami, showing our new design; FIG. 51 is a front elevational view corresponding to FIG. 50; FIG. 52 is a rear elevational view corresponding to FIG. 50; FIG. 53 is a left side elevational view corresponding to FIG. 50; FIG. 54 is a right side elevational view corresponding to FIG. 50; FIG. 55 is a top elevational view corresponding to FIG. 50; FIG. 56 is a bottom elevational view corresponding to FIG. 50; FIG. 57 is a perspective view of a ninth embodiment of a sock with the text of Florida, showing our new design; FIG. 58 is a front elevational view corresponding to FIG. 57; FIG. 59 is a rear elevational view corresponding to FIG. 57; FIG. 60 is a left side elevational view corresponding to FIG. 57; FIG. 61 is a right side elevational view corresponding to FIG. 57; FIG. 62 is a top elevational view corresponding to FIG. 57; FIG. 63 is a bottom elevational view corresponding to FIG. 57; FIG. 64 is a perspective view of a tenth embodiment of a sock with the text of Orlando, showing our new design; FIG. 65 is a front elevational view corresponding to FIG. 64; FIG. 66 is a rear elevational view corresponding to FIG. 64; FIG. 67 is a left side elevational view corresponding to FIG. 64; FIG. 68 is a right side elevational view corresponding to FIG. 64; FIG. 69 is a top elevational view corresponding to FIG. 64; FIG. 70 is a bottom elevational view corresponding to FIG. 64; FIG. 71 is a perspective view of a eleventh embodiment of a sock with the text of San Diego, showing our new design; FIG. 72 is a front elevational view corresponding to FIG. 71; FIG. 73 is a rear elevational view corresponding to FIG. 71; FIG. 74 is a left side elevational view corresponding to FIG. 71; FIG. 75 is a right side elevational view corresponding to FIG. 71; FIG. 76 is a top elevational view corresponding to FIG. 71; FIG. 77 is a bottom elevational view corresponding to FIG. 71; FIG. 78 is a perspective view of a twelfth embodiment of a sock with the text of Hawaii, showing our new design; FIG. 79 is a front elevational view corresponding to FIG. 78; FIG. 80 is a rear elevational view corresponding to FIG. 78; FIG. 81 is a left side elevational view corresponding to FIG. 78; FIG. 82 is a right side elevational view corresponding to FIG. 78; FIG. 83 is a top elevational view corresponding to FIG. 78; FIG. 84 is a bottom elevational view corresponding to FIG. 78;

FIG. 85 is a perspective view of a thirteenth embodiment of a sock with the text of Atlanta, showing our new design; FIG. 86 is a front elevational view corresponding to FIG. 85; FIG. 87 is a rear elevational view corresponding to FIG. 85; FIG. 88 is a left side elevational view corresponding to FIG. 85; FIG. 89 is a right side elevational view corresponding to FIG. 85; FIG. 90 is a top elevational view corresponding to FIG. 85; FIG. 91 is a bottom elevational view corresponding to FIG. 78; FIG. 92 is a perspective view of a fourteenth first embodiment of a sock with the text of Honolulu, showing our new design; FIG. 93 is a front elevational view corresponding to FIG. 92; FIG. 94 is a rear elevational view corresponding to FIG. 92; FIG. 95 is a left side elevational view corresponding to FIG. 92; FIG. 96 is a right side elevational view corresponding to FIG. 92; FIG. 97 is a top elevational view corresponding to FIG. 92; FIG. 98 is a bottom elevational view corresponding to FIG. 92; FIG. 99 is a perspective view of a fifteenth embodiment of a sock with the text of Boston, showing our new design; FIG. 100 is a front elevational view corresponding to FIG. 99; FIG. 101 is a rear elevational view corresponding to FIG. 99; FIG. 102 is a left side elevational view corresponding to FIG. 99; FIG. 103 is a right side elevational view corresponding to FIG. 99; FIG. 104 is a top elevational view corresponding to FIG. 99; FIG. 105 is a bottom elevational view corresponding to FIG. 99; FIG. 106 is a perspective view of a sixteenth embodiment of a sock with the text of Salt Lake City, showing our new design; FIG. 107 is a front elevational view corresponding to FIG. 106; FIG. 108 is a rear elevational view corresponding to FIG. 106; FIG. 109 is a left side elevational view corresponding to FIG. 106; FIG. 110 is a right side elevational view corresponding to FIG. 106; FIG. 111 is a top elevational view corresponding to FIG. 106; FIG. 112 is a bottom elevational view corresponding to FIG. 106; FIG. 113 is a perspective view of a seventeenth embodiment of a sock with the text of Charleston, showing our new design; FIG. 114 is a front elevational view corresponding to FIG. 113; FIG. 115 is a rear elevational view corresponding to FIG. 113; FIG. 116 is a left side elevational view corresponding to FIG. 113; FIG. 117 is a right side elevational view corresponding to FIG. 113; FIG. 118 is a top elevational view corresponding to FIG. 113; FIG. 119 is a bottom elevational view corresponding to FIG. 113;

FIG. 120 is a perspective view of a eighteenth embodiment of a sock with the text of Dallas, showing our new design; FIG. 121 is a front elevational view corresponding to FIG. 120; FIG. 122 is a rear elevational view corresponding to FIG. 120; FIG. 123 is a left side elevational view corresponding to FIG. 120; FIG. 124 is a right side elevational view corresponding to FIG. 120; FIG. 125 is a top elevational view corresponding to FIG. 120; FIG. 126 is a bottom elevational view corresponding to FIG. 120; FIG. 127 is a perspective view of a nineteenth embodiment of a sock with the text of New Orleans, showing our new design; FIG. 128 is a front elevational view corresponding to FIG. 127; FIG. 129 is a rear elevational view corresponding to FIG. 127; FIG. 130 is a left side elevational view corresponding to FIG. 127; FIG. 131 is a right side elevational view corresponding to FIG. 127; FIG. 132 is a top elevational view corresponding to FIG. 127; FIG. 133 is a bottom elevational view corresponding to FIG. 127; FIG. 134 is a perspective view of a twentieth first embodiment of a sock with the text of San Francisco, showing our new design; FIG. 135 is a front elevational view corresponding to FIG. 134; FIG. 136 is a rear elevational view corresponding to FIG. 134; FIG. 137 is a left side elevational view corresponding to FIG. 134; FIG. 138 is a right side elevational view corresponding to FIG. 134; FIG. 139 is a top elevational view corresponding to FIG. 134; FIG. 140 is a bottom elevational view corresponding to FIG. 134; FIG. 141 is a perspective view of a twenty-first embodiment of a sock with the text of Michigan, showing our new design; FIG. 142 is a front elevational view corresponding to FIG. 141; FIG. 143 is a rear elevational view corresponding to FIG. 141; FIG. 144 is a left side elevational view corresponding to FIG. 141; FIG. 145 is a right side elevational view corresponding to FIG. 141; FIG. 146 is a top elevational view corresponding to FIG. 141; FIG. 147 is a bottom elevational view corresponding to FIG. 141; FIG. 148 is a perspective view of a twenty-second embodiment of a sock with the text of Detroit, showing our new design; FIG. 149 is a front elevational view corresponding to FIG. 148; FIG. 150 is a rear elevational view corresponding to FIG. 148;

FIG. 151 is a left side elevational view corresponding to FIG. 148;
FIG. 152 is a right side elevational view corresponding to FIG. 148;
FIG. 153 is a top elevational view corresponding to FIG. 148;
FIG. 154 is a bottom elevational view corresponding to FIG. 148;
FIG. 155 is a perspective view of a twenty-third embodiment of a sock with the text of Las Vegas, showing our new design;
FIG. 156 is a front elevational view corresponding to FIG. 155;
FIG. 157 is a rear elevational view corresponding to FIG. 155;
FIG. 158 is a left side elevational view corresponding to FIG. 155;
FIG. 159 is a right side elevational view corresponding to FIG. 155;
FIG. 160 is a top elevational view corresponding to FIG. 155;
FIG. 161 is a bottom elevational view corresponding to FIG. 155;
FIG. 162 is a perspective view of a twenty-fourth embodiment of a sock with the text of Seattle, showing our new design;
FIG. 163 is a front elevational view corresponding to FIG. 162;
FIG. 164 is a rear elevational view corresponding to FIG. 162;
FIG. 165 is a left side elevational view corresponding to FIG. 162;
FIG. 166 is a right side elevational view corresponding to FIG. 162;
FIG. 167 is a top elevational view corresponding to FIG. 162;
FIG. 168 is a bottom elevational view corresponding to FIG. 162;
FIG. 169 is a perspective view of a twenty-fifth embodiment of a sock with the text of San Antonio, showing our new design;
FIG. 170 is a front elevational view corresponding to FIG. 169;
FIG. 171 is a rear elevational view corresponding to FIG. 169;
FIG. 172 is a left side elevational view corresponding to FIG. 169;
FIG. 173 is a right side elevational view corresponding to FIG. 169;
FIG. 174 is a top elevational view corresponding to FIG. 169;
FIG. 175 is a bottom elevational view corresponding to FIG. 169;
FIG. 176 is a perspective view of a twenty-sixth embodiment of a sock with the text of Charlotte, showing our new design;
FIG. 177 is a front elevational view corresponding to FIG. 176;
FIG. 178 is a rear elevational view corresponding to FIG. 176;
FIG. 179 is a left side elevational view corresponding to FIG. 176;
FIG. 180 is a right side elevational view corresponding to FIG. 176;

FIG. 181 is a top elevational view corresponding to FIG. 176;
FIG. 182 is a bottom elevational view corresponding to FIG. 176;
FIG. 183 is a perspective view of a twenty-seventh embodiment of a sock with the text of Philadelphia, showing our new design;
FIG. 184 is a front elevational view corresponding to FIG. 183;
FIG. 185 is a rear elevational view corresponding to FIG. 183;
FIG. 186 is a left side elevational view corresponding to FIG. 183;
FIG. 187 is a right side elevational view corresponding to FIG. 183;
FIG. 188 is a top elevational view corresponding to FIG. 183;
FIG. 189 is a bottom elevational view corresponding to FIG. 183;
FIG. 190 is a perspective view of a twenty-eighth embodiment of a sock with the text of Houston, showing our new design;
FIG. 191 is a front elevational view corresponding to FIG. 190;
FIG. 192 is a rear elevational view corresponding to FIG. 190;
FIG. 193 is a left side elevational view corresponding to FIG. 190;
FIG. 194 is a right side elevational view corresponding to FIG. 190;
FIG. 195 is a top elevational view corresponding to FIG. 190;
FIG. 196 is a bottom elevational view corresponding to FIG. 190;
FIG. 197 is a perspective view of a twenty-ninth embodiment of a sock with the text of Destin, showing our new design;
FIG. 198 is a front elevational view corresponding to FIG. 197;
FIG. 199 is a rear elevational view corresponding to FIG. 197;
FIG. 200 is a left side elevational view corresponding to FIG. 197;
FIG. 201 is a right side elevational view corresponding to FIG. 197;
FIG. 202 is a top elevational view corresponding to FIG. 197;
FIG. 203 is a bottom elevational view corresponding to FIG. 197;
FIG. 204 is a perspective view of a thirtieth embodiment of a sock with the text of North Carolina, showing our new design;
FIG. 205 is a front elevational view corresponding to FIG. 204;
